UNITED STATES PATENT OFFICE.

WILLIAM H. WAGGAMAN, HARRY BRYAN, AND CARY R. WAGNER, OF WASHINGTON,
DISTRICT OF COLUMBIA.

APPARATUS FOR THE MANUFACTURE OF PHOSPHORIC ACID AND COMPOUNDS OF THE SAME.

1,241,791.

Specification of Letters Patent.

Patented Oct. 2, 1917.

Application filed March 16, 1917. Serial No. 155,372.

(DEDICATED TO THE PUBLIC.)

To all whom it may concern:

Be it known that we, WILLIAM H. WAGGAMAN, HARRY BRYAN, and CARY R. WAGNER, all citizens of the United States and employees of the Department of Agriculture of the United States of America, residing in the District of Columbia, whose post-office address is Washington, District of Columbia, have invented a new and useful

10 Apparatus for the Manufacture of Phosphoric Acid and Compounds of the Same.

This application is made under the act of March 3, 1883, chapter 143 (22 Stat., 625), and the invention herein described and 15 claimed may be used by the Government of the United States or any of its officers or employees in the prosecution of work for the Government, or any person in the United States, without payment to us of any royalty

20 thereon.

Our invention relates to a new apparatus for making phosphoric acid and compounds of the same, and has for its object the production of such products and compounds 25 more expeditiously and less expensively than heretofore.

With these and other objects in view, the invention consists in the novel combinations of parts as will be more fully hereinafter disclosed and particularly pointed out in the claims.

In order that the precise invention may be more clearly understood and distinguished from prior art, it is said: It is a well known fact that phosphoric acid may be volatilized from its compounds by submitting an intimate mixture of coke, sand and the phosphate material to the action of high heat. It is generally believed, however, that the complete or nearly complete evolution of the phosphoric acid cannot be effected except at the high temperatures attainable only in the electric furnace. Since the electrical heating of low grade materials and the recovery thereby of relatively low priced products may, in some instances be commercially impracticable, it is highly desirable that such material be handled in a furnace where the cost of making the desired product is much cheaper than in an electric furnace. Although it has been stated that phosphoric acid can only be par-

tially freed from its compounds in a fuel heated shaft furnace of the ordinary blast furnace type, the inventors have found that 55 90 per cent. or more of phosphoric acid can be volatilized from mixtures of phosphate rock, silica, and coke at temperatures far below those attained in a blast furnace and concluded therefore that it was only necessary to employ a modified type of furnace and adjust the working conditions in order to obtain a high yield of phosphoric acid by means of fuel and a hot blast.

The furnace described in detail below is 65 of such a design that the phosphoric acid may be driven off as soon as it is freed from its compounds and led out of the reaction zone without being forced to pass through the green charge, thus a saving in fuel is 70 accomplished and the reduction of phosphoric acid to phosphorus is avoided. Moreover, the necessity of forcing the gaseous products through a column of relatively fine material is obviated.

Referring to the accompanying drawing forming a part of this specification, in which the figure is a vertical sectional view of apparatus built in accordance with our invention, A is the charging bell, which is of the conventional design ordinarily employed for blast furnaces. B is a chamber (built of or lined with some refractory material, C), into which the proper proportions of material are charged for the smelting operation. 85 This chamber is constructed at b in order that the charge may not work down through the shaft too rapidly. The lower end of the charge chamber, B, is some distance above the hearth or base of the furnace, the walls, 90 C, of said chamber being supported on piers or arches not shown in the figure. D is a table or platform having a sloping top for receiving the materials as they are continuously discharged from the chamber, B. E 95 are twyers for playing hot or cold blasts on the partially fused material on the platform, D. The slag thus formed runs off the table on the hearth, F, and is withdrawn from time to time through the tap hole, G. Surrounding the charge chamber, B, is the outer fume chamber, H, into which rise the volatile products of the reactions taking place on the platform, D. The more complete oxi-

dation of these fumes may be effected in the upper part of the chamber, H, by the introduction of further quantities of air through the openings, I. Finally the oxidized products are withdrawn through the exit pipe, K, in the upper part of the chamber, H, and the phosphoric acid collected in some suitable apparatus not shown in the figure.

From the foregoing it is thought that the 10 construction, operation, and many advantages of the herein described invention will be apparent to those skilled in the art, without further description, and it will be understood that various changes in the size, 15 shape, proportion, and minor details of construction may be resorted to without departing from the spirit or sacrificing any of the advantages of the invention.

Having thus described our invention, we 20 claim:

1. A blast furnace for producing phosphoric acid provided with an inner or charge chamber surrounded by, but discharging into, an outer chamber, means for introducing air into said outer chamber for burning and smelting the charge entering said chamber from the inner or charge chamber, and means for withdrawing the products of the reaction from the outer chamber, sub- 25 stantially as described.

2. A blast furnace for producing phosphoric acid provided with an inner or charge chamber surrounded by, but dis- 30

charging into, an outer chamber, a platform below the charge chamber for receiving the 35 discharge from the same, means for introducing air into said outer chamber for burning and smelting the charge upon the said platform, and means for withdrawing the products of the reaction from the outer 40 chamber, substantially as described.

3. A blast furnace for producing phosphoric acid provided with an inner or charge chamber surrounded by, but discharging into, an outer chamber, a platform below 45 the charge chamber for receiving the discharge from the same, means for introducing air into said outer chamber for burning and smelting the charge upon said platform, means for introducing a further quantity 50 of air into the upper part of the outer chamber in order to oxidize further the volatile products of the reactions, and means for withdrawing the products of the reaction from the outer chamber, substantially as de- 55 scribed.

In testimony whereof, we affix our signatures in the presence of two subscribing witnesses.

WILLIAM H. WAGGAMAN.
HARRY BRYAN.
CARY R. WAGNER.
